FIG. 1

FIG. 3

FIG. 1 is a top view the separable magnetic holder for sheet-like material showing my new design;

FIG. 2 is a side view thereof; and

FIG. 3 is a perspective view of this separable magnetic holder for sheet-like material.

The appearance of the not-shown side of the separable magnetic holder for sheet-like material device is identical to the appearance of the side shown in FIGS. 2 and 3. The bottom face of the device is plain.

I claim:

The ornamental design for a separable magnetic holder for sheet-like material, substantially as shown and described.
